UNITED STATES PATENT OFFICE.

WILLIAM E. COLLINS, OF CAMBRIDGE, NEW YORK.

BOX-FASTENER.

1,105,024.

Specification of Letters Patent.

Patented July 28, 1914.

Application filed April 23, 1914. Serial No. 833,950.

To all whom it may concern:

Be it known that I, WILLIAM E. COLLINS, a citizen of the United States, residing at Cambridge, in the county of Washington 5 and State of New York, have invented certain new and useful Improvements in Box-Fasteners, of which the following is a specification.

My invention relates to locking devices 10 for securing the lids of shipping crates or other receptacles which are used in transporting goods and which are returned when empty for refilling.

Shipping crates or boxes are subjected to 15 great strains and shocks during transportation and it is necessary to provide a very rigid and strong fastening device and yet one which may be readily unfastened. Furthermore, it is desirable that the locking 20 means should not project from the sides of the crate as it will then be more liable to injury or to catch in other goods.

The object of my invention is to provide 25 a fastening device which is substantially flush with the sides of the crate, of great strength, forming a secure lock and which may be fastened or unfastened.

In the accompanying drawings which 30 form a part of this specification, Figure 1 is a perspective view of a locking device embodying my invention with a shipping crate or box shown in outline in dotted lines to 35 illustrate the manner of applying the lock; Fig. 2, is a vertical section of the same; Fig. 3 is a horizontal section on the line 3-3 of Fig. 2; Fig. 4 is a front elevation of the lock casing; and Fig. 5 is an enlarged detail of a portion of the end wall of the 40 crate or box covered by the lock casing and showing the manner of cutting a groove or recess to receive the securing wire.

The lock casing is channel shaped having 45 a top member 2 and depending side members 3 and 4 which fit over the upper edge of the box side and are secured by screws 6. The casing may be made of any suitable metal and is preferably stamped from sheet steel. The sides hug the walls of the box side and offer no obstruction, being substantially 50 flush therewith. The stem 8 of the coöperating members of the fastener which projects from the lid is adapted to pass through a hole 10, in the top plate of the casing, and extend into the recess 12, cut in the top edge 55 of the box side. A wire 14, passed through

a transverse hole 15 in the stem 8, locks the lid of the crate rigidly and securely in closed position. It will be observed that any tendency of the lid to move upwardly is resisted by the wire 14 which bears against the underside of the top plate of the casing. To permit the curved securing or locking wire 14 to be readily passed or threaded through the hole 15 in the stem, I provide holes 18, in the front or face plate 3 of the casing, the 60 wire being preferably curved upon an arc which passes through the holes 18 and the aperture 15 of the stem. To facilitate the threading operation I provide either a single sight hole 20, or two holes 20^a, 20^b, 65 separated by an integral rib, the latter being the stronger construction. After the wire 14 has been threaded through the stem, the ends may be bent inwardly, as shown in dotted lines in Fig. 4, to securely anchor the 70 wire in position. To remove the wire it is merely necessary to bend one end back, and it may then be readily withdrawn.

The stem 8 is carried by a plate 9, which 75 may be secured to the lid by screws. While 80 the stem may be secured to the plate in any suitable manner, I prefer to provide an exceedingly strong and rigid construction and to this end I have shown the plate provided with a central boss 22, to which the stem is 85 riveted and through which it passes, surrounded by a metal filler or washer 24. This construction not only provides a strong anchorage for the stem 8, but the boss 22 which fits into a recess in the lid takes up the 90 thrusts and shocks to which the crate is subjected and relieves the strain which would otherwise be placed upon the screws and which would tend to wrench the plate from the lid.

The important advantage of my invention 95 will be apparent from the above description. It affords a lock which is substantially flush with the sides of the box or crate and is exceedingly rigid and strong. The side 100 thrusts to which the crate is subjected during the usual rough handling of transportation are transmitted to the sides and lid of the box without placing any strain upon the screws by which the stem-plate and lock 105 casing are fastened. Any direct pull tending to lift the lid is transmitted through the stem and securing plate directly to the underside of the top plate of the casing. The direct pull or thrust transmitted through the 110

stem to the wire 14 is exerted close to the stem where it cannot bend the wire but must act as a shearing strain, so that there is no tendency to loosen under repeated shocks.

While I have described in detail the particular construction illustrated in the accompanying drawings for the purpose of disclosing an embodiment of my invention, it is evident that various changes and modifications may be made therein within the scope of my claim and without departing from the spirit of my invention.

I claim:

15. A box fastener, comprising a channel shaped casing adapted to fit over the edge of a box side and having a hole in its top

member and two holes in its outer side member spaced upon either side of said first-named hole, a plate adapted to be secured 20 to the box lid and having a depending stem adapted to pass through said hole in the top member when the lid is closed, said stem being provided with a transverse hole, and a locking member adapted to be threaded 25 through said holes in said outer side member and said stem.

In testimony whereof I affix my signature in presence of two witnesses.

WILLIAM E. COLLINS.
